No. 708,093.

Patented Sept. 2, 1902.

H. M. SUTTON, W. L. STEELE & M. COERVER.
ELECTRICALLY PROTECTED STRUCTURE.

(Application filed Aug. 19, 1901.)

This technical drawing illustrates a mechanical assembly with several labeled parts:

- Top Left:** A rectangular component with a fine grid pattern, labeled 75° on its left side.
- Top Right:** A component with a stepped profile and diagonal hatching, labeled 55° on its left side.
- Bottom Left:** A component with a stepped profile and diagonal hatching, labeled 75° on its left side.
- Bottom Center:** A large rectangular component with a central rectangular cutout, labeled H above, G to the left, and T to the right.
- Bottom Right:** A component with a stepped profile and diagonal hatching, labeled 55° on its left side.
- Right Side:** A vertical component labeled 95° on its left side, with a small detail showing 95° , 94° , 94° , and 100° .
- Bottom Left Detail:** A small detail showing a stepped profile with labels 84 , 85 , 86 , 84 , 75 , 73 , 75 , 74 , 76 , and 77 .
- Top Left Detail:** A small detail showing a stepped profile with labels 75° , 75° , 75° , 75° , and 75° .
- Top Right Detail:** A small detail showing a stepped profile with labels 55° , 55° , 55° , 55° , and 55° .

UNITED STATES PATENT OFFICE.

HENRY M. SUTTON, WALTER L. STEELE, AND MICHAEL COERVER, OF DALLAS, TEXAS.

ELECTRICALLY-PROTECTED STRUCTURE.

SPECIFICATION forming part of Letters Patent No. 708,093, dated September 2, 1902.

Original application filed May 25, 1901, Serial No. 61,923. Divided and this application filed August 19, 1901. Serial No. 72,678. (No model.)

To all whom it may concern:

Be it known that we, HENRY M. SUTTON, WALTER L. STEELE, and MICHAEL COERVER, citizens of the United States, residing at Dallas, in the county of Dallas, State of Texas, have invented certain new and useful Improvements in Electrically-Protected Structures, of which the following is a specification, reference being had therein to the accompanying drawings.

This invention relates to an electrically-protected structure, and particularly to a structure embodying a series of current-conducting wires superposed in their relation to each other.

The invention has for its object to improve the construction of electrically-protected structures and is a division of our application for electric alarm system filed May 25th, 1901, Serial No. 61,923.

A further object of the invention is to provide an improved method of wiring such a structure, whereby the wires are held in position in such relation to each other that any effort to cut or tamper with the same will vary the current strength and actuate an alarm mechanism of any desired character, such as described in our application before mentioned.

Other objects and advantages of the invention will hereinafter appear in the following description and the novel features thereof will be particularly pointed out in the appended claims.

In the drawings, Figure 1 is a perspective of material prepared for the reception of the protecting-wires. Fig. 2 is a horizontal section through a protected structure similarly wired. Fig. 3 is a diagrammatic plan showing the system of wiring at right angles to each other and obliquely to each of the first-mentioned wiring. Fig. 4 is an enlarged detail indicating this method of wiring; and Fig. 5 is a detail perspective with parts broken away to illustrate the several wirings independently embodied in layers of suitable plastic material, so as to be insulated from each other.

Like characters of reference indicate like

parts throughout the several figures of the 50 drawings.

In the drawings an improved method of wiring a protected structure is shown. For instance, as shown in Fig. 1, the block or foundation for the structure is provided with 55 a series of grooves of different depths extending at an angle to each other. For instance, the groove 86 is of the greatest depth and extends parallel with one end of the block.

The groove 84 is of less depth than groove 86 60 and extends at a right angle thereto, while the grooves 85 are of less depth than the grooves 84 and extended obliquely to both of said grooves. As will be seen by the perspective view in Fig. 1, each set of these grooves 65 is composed of parallel grooves, so as to receive and contain the wires forming the protection for the structure. This is more fully shown in Fig. 2, wherein the wire 55^b is shown

in the uppermost groove, 55^a in the next lower groove, and 55^c in the deepest groove, the space between each layer of these wires being suitably filled with insulating material and the whole being coated with glue or other desired substance, as shown at 73^a, for the purpose 70 of protecting the embedded wires from atmospheric changes or other conditions adapted to affect the electrical relation of the same. This system of wiring is more fully shown by the diagram in Fig. 3, where it may be seen 75 that the wires in their superposed position form a practically continuous mesh, so that any attempt to cut through or disturb the wired surface of the protected structure will immediately cut or short-circuit the wires 85 and produce the alarm. In this figure it will be observed that the wire 55^a extends in continuous circuit longitudinally of the structure or surface to which it is applied, while the wiring 55^b is extended obliquely to the 90 wiring 55^a, and the wiring 55^c is extended transversely over both of the other wires.

In Fig. 4 the circuit 55^a is indicated by light lines, 55^b by dotted lines, and 55^c by heavy lines, and this figure shows the relation of 95 the wires to a vault or other compartment with a protected structure. The general circuit for the structure is indicated at E, while

at F one wall of the protected vault or cabinet is shown and adapted to be placed in circuit with other walls or sections G, H, and I, there being a continuous current or circuit through the several parts, as is customary in this art. The wiring when embodied in the sawed block and coated with insulating material forms practically three layers containing protecting-circuits, and, if desired, these layers may be composed in other manners than by the sawing of the block, as shown in Fig. 1. For instance, in Fig. 5 the circuit 55^c may be inclosed in one layer of insulating material, circuit 55^a in another superposed layer, and the circuit 55^b in an independent layer above the other circuits, the whole being protected by a covering 73^a, as shown by section in Fig. 2. In this latter figure a spring-contact 76 has been shown which permits the use of a door to the cabinet or vault, which when closed establishes a continuous circuit from the center of resistance to the exit of the structure, whereby the opening of the door alone breaks the circuit and sounds an alarm when the current is on. This spring-contact may comprise a bolt 76, as shown, located in a casing 74 in circuit with the several circuit-wires, while the bolt under tension of the spring 75 is pressed into contact with the plate 77, likewise in circuit with the wires upon the side wall of the cabinet.

As disclosing one means for establishing and shifting circuits through the current-conducting wires and changing the polarity thereof, we have shown at the right of Fig. 4 a main-line battery 89, having the circuit therefrom branched or split at 94, one circuit of which passes through a compensating resistance 95 and is wound upon a magnet 93, as shown by coil 100. The other branch of the circuit starting from the point 94 proceeds through one of the line-wires 94^a to the contact 4^a of the circuit-changer and shifting device 4, thence through any one of the line-wires 52^a 52^b 52^c to the protected structure, from which it returns to the current-changer 4, thence from contact 4^b to the return-wire 94^b, passing through the coil 100 in a reverse direction to the previous winding and connected to the circuit-wire 110, as shown. The condenser 96 is placed between the wires 94^a and 94^b in order to take up the back pressure and prevent sparking at the brushes upon the current-shift; but all of the parts herein mentioned have been more fully described and

claimed in our application above referred to, of which the present application is a division.

Having described our invention, what we claim is—

1. In an electrical alarm system, a wiring for a protected structure comprising a series of wires each composing an independent circuit, one of said series extending at a right angle to the other and the third series intersecting diagonally the spaces between the first two series of wires; substantially as specified. 65

2. A wiring for a protected structure comprising a block or body having on one face intersecting kerfs or grooves therein extending at a right angle to each other and of different depths, and an electrical conductor in each of said kerfs or grooves; substantially as specified. 70

3. A wiring for a protected structure comprising a block or body having intersecting kerfs or grooves therein of different depths, and an electrical conductor in each of said kerfs or grooves; substantially as specified. 75

4. In an electrical alarm system, a cabinet or apartment having the several walls or surfaces thereof provided with intersecting grooves of different depths lined by superposed insulated electrical conductors in continuous circuit; substantially as specified. 80

5. In an electrical alarm system, a cabinet or apartment having the several walls or surfaces thereof provided with intersecting grooves of different depths lined by superposed electrical conductors in continuous circuits, and insulated material for embedding each layer of said conductors; substantially as specified. 85

6. An electrical alarm system, a block or body having a series of grooves therein of different depths extending at right angles to each other and diagonally across the spaces between the right-angle grooves, circuit-wires located in said grooves and insulated from each other, and means for establishing circuits through said wires; substantially as specified. 95

In testimony whereof we affix our signatures in presence of two witnesses.

HENRY M. SUTTON.
WALTER L. STEELE.
MICHAEL COERVER.
